ARM CHAIR

Merle C. Melchior, Los Angeles, Calif., assignor of one-half to Sidney Galper, Los Angeles, Calif.

Original design application Sept. 29, 1964, Ser. No. 81,924, now Patent No. 203,437, dated Jan. 11, 1966. Divided and this application July 19, 1965, Ser. No. 86,445

Term of patent 14 years

(Cl. D15—1)

This application is a division of my co-pending application Serial No. D81,924, filed September 29, 1964, now Patent No. 203,437.

I claim:

The ornamental design for an arm chair, substantially as shown.
